UNITED STATES PATENT OFFICE.

EDWARD HUGH WILLIAMS, OF NEW ORLEANS, LOUISIANA.

SAVINGS SAFETY-BOX.

1,348,768.

Specification of Letters Patent. Patented Aug. 3, 1920.

Application filed June 2, 1919. Serial No. 301,214.

To all whom it may concern:

Be it known that I, EDWARD H. WILLIAMS, a citizen of the United States, residing at New Orleans, in the county of Orleans and State of Louisiana, have invented certain new and useful Improvements in Savings Safety-Boxes, of which the following is a specification.

My said invention relates to an improvement in safe-deposit boxes and consists of a receptacle in which valuable articles and papers may be kept and also includes a compulsory savings feature whereby the holder of the box must deposit a coin there-in before the box can be opened, all as will be hereinafter more fully described and claimed.

Referring to the accompanying drawings on which similar reference characters designate similar parts,

Figure 1 is a perspective view of a safe-deposit box showing the lid raised,

Fig. 2, a vertical longitudinal section as viewed from the line 2-2 in Fig. 1,

Fig. 3, a vertical transverse section on the line 3-3 in Fig. 1, and

Fig. 4, a detail perspective of the locking pawl.

In said drawings the part marked A represents broadly the safe-deposit box and B a separate and removable box in which the main lock C is carried.

The box A comprises a body portion 10 having a lid 11 hinged to one side thereof. A partition 12 divides the portion 10 into a large compartment 13 adapted to receive the articles for safe keeping and a smaller compartment 14 in which the box B is located. The said box B is likewise composed of a body portion 15 having a hinged lid 16 adapted to be secured in its closed position by a lock 17 as shown in Fig. 3. A coin chute 18 is secured within the portion 15 and opens through the top of the portion 15 where it communicates with a similar opening 19 formed in the lid 11 and through which the coins are introduced. The lock C comprises a locking pawl 20 mounted to swing on a pivot 21 secured into a suitable frame 22 and provided at its upper end with a latch member 23 adapted to enter an opening 24 in a lug 25 depending from the under side of the lid 11. At a point midway between the pivot 21 and latch member 23 is a shoulder 26 against which normally bears a lug 27 formed adjacent one end of a rocking

member 28 which is pivoted on a short shaft 29 similar to the pivot 21. The opposite end of the member 29 is located adjacent the inner end of the chute 18 and is grooved to receive and temporarily retain the coin as described later. Below the pivot 21 the pawl 20 is curved to one side as at 30 and has one arm 31 of a bell-crank lever 32 resting upon it. The arm 33 of the bell-crank lever lies in the path of movement of the grooved portion of the rocking member 28 for a purpose to be explained later. In order to prevent an unauthorized person from opening the lock, I provide a safety pawl 34 which swings freely upon a pivot 35 and which is provided at its upper end with a projection 36 which normally lies just out of the path of movement of a projecting segment 37 formed on the rocking member 28 adjacent the lug 27, but which swings into the path of movement of the segment 37 when the box is tilted slightly. A leaf spring 38 bears against the portion 30 of the pawl 20 to normally hold the pawl in its locked position.

The entire box B is held in position by forming a finger 39 upon the cover member 14, which finger 39 engages within a slot formed in the partition wall 12. A U-shaped latch member 40 is pivoted at one end to the partition 12 and covers the upper edge of the partition 12 resting upon the finger 39. As shown at Fig. 1, the latch member 40 is of such length that with the hasp 25 engaged in the lock by the bolt 23 any attempt to raise the box B out of the compartment would necessarily lift the end of the latch 40 which is not pivoted. This lifting of the latch would cause such latch to engage against the cover member 11 and prevent the further lifting of any of the parts. As shown particularly at Fig. 3 the cover member 11 bears directly upon the top of the latch 40 whereby any movement is prevented by reason of the parts being pivoted to the partition 12 which is rigid and stationary in the box A.

The operation of unlocking the box A is as follows: A coin having been deposited in the opening 19, passes down the chute 18 and falls into the grooved portion of the member 28 lowering this end of the member 28 until it rests upon the lever 33 thereby causing the lug 27 to rise out of the path of movement of the shoulder 26. A key of suitable form is then turned to bear

against the edge of the pawl 20 and move it laterally against the tension of the spring 38. This lateral movement causes the end 30 of the pawl 20 to swing downward there-
5 by rocking the lever 32 which allows the member 28 to lower and deposit the coin into the box B. By leaving the key in the position of holding the pawl 20 in its un-
locked position, the reverse operation may
10 be performed to lock the box, whereas if the key is turned beyond the position of unlocking the box, it will be necessary to deposit another coin in order to release the pawl 20.
15 Having thus fully described my said in-
vention, what I claim as new and desire to
secure by Letters Patent, is:
20 1. A safe-deposit box having a hinged lid,
a partition within said box forming com-
partments therein, a casing within the box
having a hinged lid located in one of said
compartments, means for locking the lid of
25 said inner casing, and means carried within
said inner casing for locking the lid of the
box, substantially as set forth.
30 2. A receptacle of the class described com-
prising an outer casing having a hinged lid,
a partition within said casing forming com-
partments therein, an independently locked
35 removable casing located in one of said com-
partments, a lock located within said inner
casing comprising a pivoted pawl having a
hook at its upper end, a staple depending
from the lid of said outer casing and pass-
40 ing into said inner casing and adapted to
co-act with said hook, means for holding
said pawl in its locked position, and a safety
pawl to prevent accidental opening of said
lock, substantially as set forth.
45 3. In a receptacle of the character de-
scribed the combination of an outer box
with a lid, a coin-operated locking mecha-
nism for the lid, and an inner box within
said outer box containing said locking mech-

anism and also provided with a lid con-
trolled by a separate lock, substantially as
set forth. 45

4. A safe-deposit box provided with a key
lock released by a coin-operated mechanism,
and a separately locked inner receptacle 50
within said box containing said mechanism
and adapted to receive and retain the coin,
substantially as set forth.

5. A safe-deposit box provided with a lid,
a receptacle within said box provided with 55
another lid, a lock for the lid of said box
contained within said inner receptacle and
controlled by coin-operated mechanism, and
a separate lock for said inner receptacle,
substantially as set forth. 60

6. A safe-deposit box provided with a lid,
a key-lock for retaining the lid in locked
condition, means to prevent the actuation
of the key-lock, and means actuated from an
inserted coin for releasing the lock retain-
ing means. 65

7. A safe deposit box provided with a lid,
a partition forming two compartments in
the box, a second box slidably inserted in
one of the compartments, a lock located in 70
the second box adapted to engage the lid
of the main box, a detent inclosed within
the second box normally preventing the
actuation of the lock, means whereby an in-
serted coin removes the detent permitting
75 the actuation of the lock, and a second in-
dependent lock for locking the contained
box, such lock being available only when
the second box has been removed from the
main box. 80

In witness whereof I have hereunto set
my hand and seal at New Orleans, Louisi-
ana, this 30th day of May, A. D. nineteen
hundred and nineteen.

EDWARD HUGH WILLIAMS. [L. S.]
